UNITED STATES PATENT OFFICE.

ROBERT J. DAVIS, OF CHICAGO, ILLINOIS, ASSIGNOR TO EMILY V. METHVEN, OF CHICAGO, ILLINOIS.

BINDER.

1,156,467.

Specification of Letters Patent. Patented Oct. 12, 1915.

Application filed September 28, 1914. Serial No. 863,821.

To all whom it may concern:

Be it known that I, ROBERT J. DAVIS, a citizen of the United States, residing at Chicago, in the county of Cook and State of Illinois, have invented a new and useful Improvement in Binders, of which the following is a specification.

My invention relates to certain new and useful improvements in binders and is fully described and explained in the specification and shown in the accompanying drawings, in which:

Figure 1 is a perspective view of the binder embodying my invention; Fig. 2 is a plan showing the binder open; Fig. 3 is a plan of the opened binder showing the method of use and Fig. 4 is a section on the line 4 of Fig. 1.

Referring to the drawings, 5 is one of the cover-sections, which has along its edge a hinged strip 6 provided with perforations 7 through which are passed the two ends of the cord 8. The papers to be bound are perforated near one margin so as to register 20 with the perforations 7 in the hinged strip 6 and the two ends of the cord are passed through the papers. 9 is the other cover, same being provided with a hinged strip 10. In the preferred form of construction the 25 hinged strip is sufficiently removed from the cover, or the hinge connecting the cover to the strip 10 is sufficiently wide that the hinged strip can be turned over on the cover and lie parallel and in contact therewith. Thus when the papers are in position the 30 hinged strip will turn inward and be enclosed by the cover, as shown in Fig. 1. This method of concealing the binder-cord is well known in this art and can be embodied in or omitted from my binder, as desired. It will be evident that if there is no objection to having the ends of the cord 35 visible the cover 9 can be turned around so that, when the binder is closed, it lies in the same plane with the strip 10, instead of covering same in the parallel plane, and in such case, of course, the ends of the cord will be visible.

The cords pass through perforations 11 in 40 the strip 10 and are secured in place by sheet metal spring-clips, whose construction is quite clearly shown in Fig. 4. Each clip consists of a flat part 12, secured to the hinged-strip 10 by an integral prong 13 and

55 rivet 14, and a re-curved part 15 providing between itself and flat part 12 a space to engage and confine the binding cord. The re-curved part 15 is perforated at 16 over the head of the rivet 14. This affords an almost necessary means of getting the rivet 60 into place, and the rivet itself, when in position, affords a stop for the cord so that it cannot be pulled back against the sharp edges of the clip on which it might be worn. There is sufficient spring in the clip to admit cords of practically any size which it 65 may be desired to use, and the ends of the clips are slightly up-turned at 17 to permit the ready insertion of the cord.

It is found in practice that the clip thus 70 described affords a very simple and efficient means for holding the binder cord in position, that it permits the use of very large cord when necessary to handle thick bunches 75 of paper, and that the securing of the cord therein can be accomplished very quickly. The free ends of the cord may, if desired, be tied together, and this will doubtless be desirable when using a long cord, and the 80 clips are turned outward in opposite directions; so that any tension put upon the ends of the cord in tying them will tend to pull the cord deeper into the clips rather than to pull it out.

I realize that considerable variation is 85 possible in the details of the construction herein shown, and I do not intend to limit myself thereto, except as pointed out in the following claims, in which it is my intention to claim all the novelty inherent in the 90 device as broadly as is permitted by the state of the art.

I claim as new and desire to secure by Letters Patent:

1. A binder comprising two cover-members, cords having their free ends passed from one cover through perforations in the other, and clips on the last-named cover-member, said clips being formed of sheet metal bent upon itself to form flat hook-like 95 members riveted to the cover and rivets whereby the clips are secured to the cover, said rivets having their heads lying between the surfaces of the hook to form an abutment for the cord.

2. A binder comprising two cover-members, cords having their free ends passed from one cover through perforations in the 100

other, and clips on the last-named cover member, said clips being formed of sheet metal bent upon itself to form flat hook-like members riveted to the cover, and rivets 5 whereby the clips are secured to the cover, said rivets having their heads lying between the surfaces of the hook to form an abutment for the cord, the upper part of the

clips being perforated to permit the introduction of the rivets.

In testimony whereof I have hereunto set my hand.

ROBERT J. DAVIS.

In presence of two subscribing witnesses:

JOSEPH SCHWARTZ,

FLORENCE RONDEAU.
